CLAIM

USPC **D9/415**

The ornamental design for packaging for batteries, as shown and described.

(58) **Field of Classification Search**

DESCRIPTION

USPC D9/415, 418, 424, 732
CPC B65D 75/327; B65D 75/36; B65D 75/366;
B65D 75/367; B65D 75/32; B65D
2575/3245; B65D 75/326; B65D
2575/366; B65D 2585/88; B65D 75/322;
B65D 77/2032; B65D 5/4204; B65D
75/22; B65D 77/0413; B65D 5/4208;
B65D 77/02; B65D 25/22; B65D
75/5833; B65D 85/00; B65D 2543/00194;

FIG. 1 is a top perspective view of a packaging for batteries showing our new ornamental design;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

The broken lines shown represent unclaimed subject matter and form no part of the claimed design.

(Continued)

The figures are lined for the colors black and copper, wherein black is represented by a solid fill and copper is represented by cross-hatching.

1 Claim, 5 Drawing Sheets
